BOOSTER PUMP

Ralph G. Denk, Peru, Ind.

Application February 28, 1931, Serial No. 519,232
Renewed December 6, 1933

2 Claims. (Cl. 103—89)

This invention relates to booster means for hot water heating systems and one feature of the device is the provision of a structure whereby the circulation of the water will be uniform throughout the entire system.

A further feature of the invention is the provision of a booster means whereby a plurality of return pipes may be connected with a single booster or pump structure.

10 A further feature of the invention is the provision of means for positively directing the flow of the water as it passes through the booster device.

15 A further feature of the invention is in so arranging the booster mechanism that a positive circulation will result without increasing the boiler pressure.

20 A further feature of the invention is the provision of means for so mounting the motor employed in connection with the booster mechanism that vibration will be eliminated.

25 A further feature of the invention is the provision of means for directing water through bearings associated with the device and providing a water bearing.

Other objects and advantages will be herein-after more fully set forth and pointed out in the accompanying specification.

30 In the accompanying drawings which are made a part of this application,

Figure 1 is a side elevation of the booster mechanism.

Figure 2 is a sectional view thereof as seen along line 2—2, Fig. 1.

35 Figure 3 is a vertical transverse sectional view as seen along line 3—3, Fig. 2.

Figure 4 is a similar view as seen from line 4—4, Fig. 2.

40 Figure 5 is an elevation of the boiler portion of a heating plant with the booster mechanism attached thereto.

Figure 6 is an elevation of a modified form of booster mechanism, and,

45 Figure 7 is an elevation of still a different form of booster mechanism.

Referring to the drawings in which similar reference numerals designate corresponding parts throughout the several views, the numeral 1 designates the conventional form of water heating 50 boiler, with which are associated water conveying pipes 2, which pipes extend to and are connected with conventional radiators (not shown).

55 In heating plants of this nature it is customary to depend on the heated water to replace the cooler water and cause the cooler water to return

by gravity to the boiler structure 1, but as some of the radiators are at a higher elevation than others and at a greater distance from the boiler than others, the flow of the water in some of the pipes is more sluggish than in others, thus creating a greater degree of heat in some of the radiators than in others.

To overcome these objectionable features and cause substantially the same degree of heat in all the radiators, at whatever distance from, or at 65 whatever elevation they may be with respect to, the boiler, a drum or pump casing 3 is provided, said drum having ports 4 through the wall thereof, to which the return pipes 2 are connected. Within the drum 3 is a booster impeller structure 70 5, which creates a suction through the pipes 2 and returns the water into the boiler 1 through a coupling 6, said impeller structure being carried by a shaft 7, extending through one end of the drum, the impeller structure 5 being preferably 75 mounted within the coupling 6 and beyond the drum 3.

As the impeller structure 5 is positioned at one side of the flow of the water on entering the drum 3, a deflector 8 is extended inwardly from one 80 head wall 9 of the drum, said deflector being tapered from its point of connection with the head 9 to the opposite end thereof, the peripheral face of the deflector having a plurality of spaced wings 10 extending from end to end thereof, the wings 85 preventing the water from one pipe 2 from passing directly through the drum into a pipe 2 at the opposite side of the drum, while the tapered faces of the deflector 8 will cause the water discharging from the several pipes 2 to travel toward the 90 coupling 6.

The shaft 7 extends through suitable bearings 11 and 12 and has thrust bearings 13 and 14 associated therewith, the outer end of the shaft 7 being connected to a motor 15, through the medium of which the shaft 7 and impeller structure 5 are driven.

The motor 15 is mounted on a base 16, to which the booster element is also attached, a plate of wood 17 or the like being introduced between the motor and base; and in order to eliminate undue vibration of the motor, a section of rubber 18 or similar resilient material is entered between the plate of wood 17, and the base 16, while washers 19 of rubber or similar material are introduced between the feet of the motor and the plate 17. The plate 17 is secured to the base 16 by extending screws 20 or the like through the base 16 and interposed section of rubber 18, into the plate 17; while 110

the motor is secured to the plate 17 by extending bolts 21 through the feet of the motor, interposed washers 19 and plate 17.

In order to provide a water bearing for the 5 shaft 7, a bolt 22 or the like is extended transversely through the shaft 7, with a head 23 at each end thereof so that as said shaft is rotated, said heads will set up a suction in the cavity 24 and draw water through slots 25 in 10 the bearing 11, such water being in turn expelled from the cavity 24 through bores 26 in the deflector 8.

In Figs. 6 and 7, different forms of booster pumps are shown, these structures being provided with heads 27, into which the return water is entered through pipes 2' and said heads are so arranged that any number of the return pipes 2' may be connected therewith.

While the description and drawings illustrate 20 in a general way certain instrumentalities which may be employed in carrying the invention into effect, it is evident that many modifications may be made in the various details without departing from the scope of the appended claims, it being understood that the invention is not restricted to the particular examples herein described.

What I claim is:

1. A fluid impelling mechanism having a 30 casing, a journal wall at one end of said casing, an outlet structure at the other end of said casing, a shaft bearing in said journal wall disposed centrally of the casing, inlets in said casing directed radially towards said shaft, an impeller mounted on said shaft within said casing, serving to draw fluid through the casing from said inlets, a journal boss carried by said journal wall, said boss extending inwardly into the path of the fluid coming in from the inlets and serving to guide same to said outlet structure, a journal in the end of said boss for supporting said shaft, fluid communications extending from the interior of said casing longitudinally through said journal and said boss, 45 other communications uniting with and transverse to the first mentioned communications between said journal wall and said journal and

passing through said boss transversely to the axial center thereof, transverse extensions on said shaft serving to propel fluid through said communications in the opposite direction to the movement of fluid created by said impeller, said extensions being within said boss in the line of said communications, whereby part of the fluid drawn into said inlets and through said casing by said impeller will enter said journal at the end of said boss and move contradirectional to the other fluid passing through said casing and join the incoming stream of fluid, between said journal and said journal wall.

2. A fluid impelling mechanism having a casing, a journal wall at one end of said casing, an outlet structure at the other end of said casing, a shaft bearing in said journal wall disposed centrally of the casing, inlets in said casing directed radially towards said shaft, an impeller mounted on said shaft within said casing, serving to draw fluid through the casing from said inlets, a journal boss carried by said journal wall, said boss extending inwardly into the path of the fluid coming in from the inlets and serving to guide same to said outlet structure, a journal in the end of said boss for supporting said shaft, a fluid communication extending from said journal to said bearing, another communication uniting with the first mentioned communication and terminating through the surface of said journal boss between said journal wall and said journal, transverse extensions on said shaft serving to propel fluid through said communications in the opposite direction to the movement of fluid created by said impeller, said extensions being rotated within said boss through the line of both of said communications, whereby the fluid drawn into said inlets and through said casing by said impeller which enters said journal will move through the second mentioned communication contradirectional to the other fluid passing through said casing and join the incoming stream of fluid, between said journal and said journal wall, and be thus sufficiently diverted from said bearing to prevent leakage through same.
